HOLDER FOR COLORED LIGHT SCREENS

Filed July 26, 1923

By John J. Barker,
his attorney

UNITED STATES PATENT OFFICE.

PAUL J. TIMBERLAKE, OF JACKSON, MICHIGAN.

HOLDER FOR COLORED LIGHT SCREENS.

Application filed July 26, 1923. Serial No. 653,981.

To all whom it may concern:

Be it known that I, PAUL J. TIMBERLAKE, a citizen of the United States, residing at Jackson, in the county of Jackson and State 5 of Michigan, have invented certain new and useful Improvements in Holders for Colored Light Screens, of which the following is a specification.

My invention relates to holders for colored transparent light screens such as are used in the illumination of show windows and other places; and has for its object to produce a holder for the thin sheets employed for this purpose that may be cheaply 15 manufactured, easily applied to the shade or reflector of a lamp with which the screen is to be used, and which may be applied to and secured upon shades of widely different shapes and sizes.

20 In the accompanying drawings I have illustrated one, and the preferred, form of my invention, in which—

Figure 1 is a perspective view of a holder embodying the invention applied to the shade or reflector of an electric lamp;

Fig. 2 is a plan view of the holder; and

Fig. 3 is a transverse sectional view taken on the line III—III of Fig. 2.

Fig. 4 is a perspective view showing a different form of the invention from that illustrated in the other views.

Referring to these drawings, A designates an electric lamp fixture, B a shade or reflector carried thereby, and C a color sheet of thin transparent material through which the light from the lamp passes for securing colored illuminating effects.

The invention consists of a holder for the color sheet C adapted to be applied to the 40 open end of the shade or reflector B of the lamp in such manner that it covers the open end of the shade, resting against the edge thereof, so that the light from the lamp must pass through the screen. The holder consists 45 of a marginal frame 2, preferably formed of stiff wire and of the desired shape, as for instance, square. Crossing the frame 2 are a series of longitudinal wires 3, and another series of transverse wires 4. These wires 50 cross each other as represented, but are spaced apart at their intersections sufficiently to permit the sheet C to be slipped between the wires, for instance, overlying the longitudinal wires 3 and underlying the transverse wires 4, as best represented in Fig. 3.

55 5, 5 indicate a pair of fingers extending

diagonally part way across the frame from the corners at one end thereof. The ends of these fingers are upturned as indicated at 6 to constitute stops adapted to engage with 60 the edge of the shade or reflector to which the screen holder may be applied.

Along the opposite sides of the frame, and preferably located above the upper surface formed by the intersecting wires 3, 4, are 65 wires 7, 7 constituting runners on which are supported a coiled spring, or springs, as will be described. The ends of the wires constituting the runners are bent to form legs 8 which are secured to the side bars of 70 the marginal frame 2. The legs toward the end of the frame to which are secured the fingers 5 are extended sufficiently to cross the frame 2 and project somewhat below it, as indicated at 9.

75 A coiled spring is supported upon the runners. Its middle portion extends across the frame from one runner 7 to the other, as indicated at 10; intermediate portions, 11, 11, at either end of the part 10, surround the 80 runners 7, and end portions 12 are coiled about the projecting ends 9 of the runners 7. A single spring thus has five parts, two end portions encircling the ends 9 of the runners, and serving to hold the spring in place; two intermediate portions 11 coiled about 85 the runners 7 and adapted to be more or less extended when the holder is applied to a lamp shade or reflector, as indicated in Fig. 1, and by dotted lines in Fig. 2; and the 90 central portion 10 that is adapted to be sprung over the edge of the shade B and serving to retain the holder in position across the face of the shade or reflector. Of course 95 a pair of springs could be used instead of one, their inner ends being adapted to be united by a connecting piece 10' shaped to conform to the edge of the shade, preferably formed at its center into a finger piece by which it may be manipulated, as represented 100 in Fig. 4, but for some purposes I prefer to use a single spring, as represented in Figs. 1 to 3, as that is more satisfactory in use.

105 In using my invention a color sheet C of suitable material, as for instance, thin transparent celluloid, is slipped between the cross wires 3 and 4 of the frame. The latter is then applied to the lamp, as represented in Fig. 1. The edge of the shade is first caused to rest against the stops formed by the upturned ends 6 of the fingers 5, and then the free, intermediate, elastic, portions 10 of

the spring is stretched until it is caused to spring over the edge of the shade. In stretching the spring over the edge of the shade the portions 11 will be more or less expanded or stretched according to the size of the shade.

The spring forms a resilient attaching means that will hold the frame securely and is easily manipulated whenever the frame is to be applied to or removed from a lamp shade.

My invention is primarily intended as a holder for sheets adapted to be used in connection with lamps for securing colored illumination effects, but it is apparent that it is equally adapted to holding other objects than transparent color sheets, and that the holding frame is adapted to be applied to the edge of other articles than lamp shades, and hence I wish it to be understood that my invention is adapted for other uses than the single one in connection with which it is herein specifically described.

What I claim is:

1. A holder for a flat sheet, comprising a frame in which the sheet is held, adapted to cover the open end of a shade for a lamp, and an elastic attaching means for detachably uniting the holder to the shade, the ends of which are secured to the holder at the opposite sides thereof, and its intermediate portion being free and arranged to be sprung over and encircle to a certain extent the peripheral edge portion of the shade.

2. A holder for a sheet of material, consisting of a frame, an extensible spring securing means extending across the frame and connected therewith near the opposite edges thereof, and fixed stops, the stops being arranged to engage with the edge of a lamp shade and the said cross securing means being arranged to be sprung over the edge of the shade opposite that portion which engages the said stops.

3. A holder for a sheet of material, consisting of a frame formed of crossed wires

between which may be slipped the sheet to be held, and a spring connected with the frame near its opposite edges and extending across the frame and adapted to be sprung over the edge of a shade to hold the frame in engagement with said shade.

4. A holder for a sheet constituting a light screen, consisting of a frame, crossed wires between which the sheet is placed, bars at the opposite edges of the frame and a coiled spring, the end portions of which surround the said bars and the intermediate, extensible, portion of which extends across the frame and is adapted to be sprung over the edge of a lamp shade.

5. A holder for a light screen, consisting of a flat frame having crossed wires between which the sheet constituting the screen may be slipped, stops near one end of the frame, bars at the sides of the frame, and a coiled spring, the end portions of which surround the said bars and are movable thereon as the said portions are extended, and the intermediate portion of the spring extending across the frame from one bar to the other, the frame being adapted to be applied to a lamp shade the edge of which engages with the said stops, while the portion of the spring extending across the frame is sprung over the edge of the shade.

6. A holder for a light screen, consisting of a flat wire frame to hold the sheet constituting the screen, fingers extending diagonally part way across the frame from two of the corners thereof and bent at their ends to constitute stops, bars of wire at the opposite sides of the frame, the bars having their ends bent to constitute legs which are securely united to the frame, the legs nearest one end extending across and below the frame, a coiled spring, the intermediate portion of which extends across the frame and the end portions of which surround the side wire bars and the extreme end portions of which surround the extensions of the legs of the wire bars, all as herein described.

PAUL J. TIMBERLAKE.
